Patented Dec. 8, 1914.

UNITED STATES PATENT OFFICE.

ERNEST W. PLEGER AND WILLIAM M. WELLMANN, OF DETROIT, MICHIGAN.

GARMENT-RECEPTACLE.

1,119,986.

Specification of Letters Patent.

Patented Dec. 8, 1914.

Application filed April 8, 1914. Serial No. 830,341.

To all whom it may concern:

Be it known that we, ERNEST W. PLEGER, a citizen of the United States, and WILLIAM M. WELLMANN, a subject of the Emperor of Germany, residing at Detroit, in the county of Wayne and State of Michigan, have invented certain new and useful Improvements in Garment-Receptacles, of which the following is a specification, reference being had therein to the accompanying drawings.

This invention relates to a garment receptacle, and the primary object of our invention is to provide a novel, impervious, flexible receptacle or container for garments or other articles, in which a suitable disinfectant, deodorant or exterminating agent can be placed for disinfecting, fumigating or exterminating moths, vermin, etc.

Another object of our invention is to provide a durable, inexpensive and easily handled garment receptacle or bag that permits of garments or other articles being safely stored, preserved and protected against deterioration or deleterious forces under any climatic conditions.

A further object of our invention is to provide a bag-like container for garments having a novel closure that permits of the container being made air tight whereby disinfecting and fumigating agents can be injected into the container or such agents placed therein without danger of gases or fumes escaping from the container.

With the above and other objects in view, our invention resides in the novel construction, combination and arrangement of parts to be hereinafter specifically described and then claimed.

Reference will now be had to the drawings, wherein—

Figure 1 is a perspective view of a garment receptacle partly broken away; Fig. 2 is an enlarged cross sectional view of the closure of the garment receptacle, and Fig. 3 is an enlarged detail sectional view of a suspension member of the garment receptacle.

In the drawing 1 denotes an inverted bag-like receptacle or container made of a flexible, impervious material, as rubberized silk, and the receptacle is made of a sufficient size to accommodate a garment hanger or garments without necessarily folding or crumpling the garment, thereby permitting of the

same being maintained in shape for immediate use.

The closed end of the receptacle has central inner and outer reinforcing strips 2 made of leather or a material similar to the receptacle and cemented or otherwise connected to the inner and outer sides of the receptacle. The outer reinforcing strip retains the angle end 3 of a hook or suspension member 4 in engagement with the receptacle without perforating the same, and said hook or suspension member permits of the receptacle being hung in a closet, upon a rack or from a suitable support. The inner reinforcing strip 2 retains the angle end 5 of a loop or suspension member 6 in engagement with the inner side of the receptacle, without perforating the same, said loop or suspension member 6 permitting of a garment hanger 7 being placed in the receptacle to support garments 8 therein. The members 4 and 6 vertically aline whereby the receptacle 1 can be properly balanced relatively to a support to maintain the garment within the receptacle in proper shape and form. With the suspension members centrally of the closed end of the receptacle, the walls of the receptacle can be maintained in spaced relation to the contents thereof when the receptacle is made of a suitable material.

The edges of the receptacle, at the open end thereof, are provided with a continuous case 9 in which is placed felt 10 or other yieldable or compressible material. The case or cases are preferably upon the inner side of the receptacle and when it is desired to close the same, the open end of the receptacle is flattened and a strip of felt 11 placed between the confronting sides of the case or cases 9, although in some instances the intermediate strip of felt can be dispensed with. Cleats or clamping strips 12 are then placed in engagement with the open end of the receptacle, one of said cleats having socket members 13 and the other cleat set screws 14 adapted to enter the socket members and secure the cleats upon the open end of the receptacle, with the case or cases 9 under compression, thereby providing an air tight closure. The socket members 13 and the set screws 14 constitute means for clamping the cleats upon the open end of the receptacle, and it will be noted that by resorting to such means the open end of the

receptacle is not perforated, but is maintained intact. Adjacent to the open end of the receptacle, a side wall thereof has a pocket or holder 15 for a vial or small receptacle 16 adapted to contain a disinfecting, fumigating or deodorizing agent. The receptacle 1, adjacent to the open end thereof, has an intake connection or nipple 17 of that type generally used in connection with 10 pneumatic tires. Detachably connected to the nipple is a flexible conduit or tube 18, which can be connected to a compressible bulb, pump or other device 19 whereby ether, gas or the fumes of a suitable disinfectant 15 or deodorant can be injected into the receptacle.

From the foregoing it will be observed that the receptacle has provision whereby various preservatives or vermin exterminators can be placed in the receptacle, and with the garment receptacle made of a suitable material it can be easily and quickly placed over a garment or a garment placed therein when it is desired to use the same, 25 and when not in use it can be rolled or folded to occupy a comparatively small space.

We attach considerable importance to the simplicity of construction, and while in the 30 drawing there is illustrated a preferred embodiment of our invention, it is to be understood that the structural elements are susceptible to such changes, as in the size, shape and manner of assemblage, as fall within 35 the scope of the appended claims.

What we claim is:

1. A garment receptacle comprising a con-

tainer having an open end, cleats adapted to be clamped in engagement therewith to close the open end of said container, and 40 an intake connection adjacent the open end of said container whereby a vermin exterminator can be injected in the container.

2. A garment receptacle comprising an inverted bag, reinforcing members secured to the closed end thereof, suspension members retained in engagement with said bag by 45 said reinforcing members, a compressible case carried by the edges of said bag at the open end thereof, cleats adapted to be 50 clamped upon the open end of said bag to close the same, and a pocket carried by the inner side of said bag adjacent to the open end thereof.

3. A garment receptacle comprising an inverted bag, reinforcing members secured to the closed end thereof, suspension members retained in engagement with said bag by 55 said reinforcing members, a compressible case carried by the edges of said bag at the open end thereof, cleats adapted to be 60 clamped upon the open end of said bag to close the same, a pocket carried by the inner side of said bag adjacent to the open end thereof, and means carried by said bag adjacent to the open end thereof whereby gases 65 can be injected into said bag.

In testimony whereof we affix our signatures in presence of two witnesses.

ERNEST W. PLEGER.

WILLIAM M. WELLMANN.
